UNITED STATES PATENT OFFICE.

MINOR HARRIS, OF HARTINGTON, NEBRASKA.

GRINDING-MACHINE.

1,176,218.

Specification of Letters Patent. Patented Mar. 21, 1916.

Application filed May 6, 1915. Serial No. 26,236.

To all whom it may concern:

Be it known that I, MINOR HARRIS, a citizen of the United States, residing at Hartington, in the county of Cedar and State of Nebraska, have invented certain new and useful Improvements in Grinding-Machines; and I do hereby declare the following to be a full, clear, and exact description of the invention, such as will enable others skilled in the art to which it appertains to make and use the same.

My invention relates to new and useful improvements in grinding machines and more particularly to that class adapted to be used for grinding food for live stock, fowls, etc., and my object is to provide a grinding machine that may be very cheaply, as well as strong and durably constructed.

A further object is to so construct the device that horse power may be applied thereto to operate the same.

A further object is to provide means for regulating the crushing rollers for fine or coarse grinding. And a further object is to provide means for causing the crushing rollers to travel toward each other when the driving mechanism is rotated either to the right or left.

Other objects and advantages will be hereinafter set forth and more particularly pointed out in the accompanying specification.

In the accompanying drawings which are made a part of this application, Figure 1 is a vertical sectional view through the grinding machine. Fig. 2 is a horizontal sectional view as seen on line 2—2 of Fig. 1, with part of the device omitted. Fig. 3 is a sectional view through the upper portion of the device as seen on line 3—3 of Fig. 1. Fig. 4 is a top plan view of the power applying gear removed, and Fig. 5 is a plan view of the frame portion of the device.

Referring to the drawings in which similar reference numerals designate corresponding parts throughout the several views, 1 indicates the supporting frame of the grinder, which is preferably in the form of a ring, to which are attached any suitable form of supporting legs 2, the upper face of the supporting frame having ears 3 extending upwardly therefrom and arranged in pairs, between which are rotatably mounted friction rollers 4 for the reception of the base 5 of the driving gear 6.

The driving gear 6 is constructed in circular formation and the base member thereof extends laterally from the lower edge of the driving gear so as to form a face to bear upon and travel over the rollers 4 when the driving gear is rotated, and in order to retain the gear in position over the rollers, straps 7, or the like, are attached to the outer edge of the supporting frame 1 and have their upper ends bent inwardly and extended over the upper face of the base 5, thus retaining the driving gear in position over the rollers.

Supported from the frame 1 by means of brackets, or the like 8, is a housing 9 which is preferably constructed oblong and has mounted therein a pair of crushing rollers 10 and 11 which extend longitudinally of the housing and find bearings in the end walls thereof, said rollers having shafts 12 and 13 respectively extending from each end thereof to receive pinions 14 and 15 respectively, the teeth of which mesh with the teeth 16 of the driving gear 6 and which cause said rollers to revolve when the driving gear is operated.

Each crushing roller is provided with but one pinion and in order to cause the rollers to rotate toward each other when the driving gear 6 is given a right hand drive, the pinion 14 is engaged with the shaft 12 at the left hand end of the roller, while the pinion 15 is attached to the shaft 13 at the right hand end of the roller 11, but should the driving gear be given a left hand drive, the two gears should be shifted to opposite ends of their respective crushing rollers.

Extending upwardly from the housing 9 and supported by the end walls thereof is a hopper 17, which is preferably flared and has its lower end terminated immediately above the crushing rollers 10 and 11, the opening at the lower end of the hopper being of less width than the combined width of the two crushing rollers, thereby causing the grain, etc., contained within the hopper to pass between the rollers.

Extending longitudinally through the hopper 17 is an agitator 18 having fingers 19 thereon, and when rotated will agitate and feed the contents of the hopper into engagement with the rollers. One end of the agitator has a shaft 20 projecting therefrom, the outer end of which carries a gear 21, which gear meshes with the gear 14 to cause

the agitator to rotate when the mill is operated.

In order to regulate the amount of grain, etc., admitted to the rollers for crushing purposes, a slide 22 is introduced through one wall of the hopper, adjacent its lower end, and by moving the slide inwardly or outwardly, the amount of grain, etc., being fed to the rollers may be regulated.

10 The roller 11 has its shaft 13 extended through elongated slots 23 in the end walls of the housing and coöperating with said shafts 13 are bearing blocks 24 which blocks coöperate with adjusting screws 25 extending through threaded openings in the wings 26 at each end of the housing 9, the outer ends of the adjusting screws preferably having hand wheels 27 thereon for turning said screws to adjust the roller 11 toward or from 15 the roller 10 whereby the product will be ground to a finer or coarser degree.

The gear 6 is rotated in any preferred manner, but preferably by attaching a sweep 28 to the vertical face of the gear, to which 25 a draft animal is hitched, a lead pole 29 being also attached to the gear 6 at a distance from the sweep to properly guide the animal in its travel around the mill.

In view of the simplicity of this device, it 30 can be very cheaply constructed and at the same time rendered strong and durable, and by providing the adjusting screws for one of the rollers, the food may be ground to a finer or coarser degree as the occasion may 35 require.

It will likewise be seen that by mounting the driving gear upon the friction rollers 4, as shown, the mill may be easily operated in view of the light running qualities of the 40 parts.

Copies of this patent may be obtained for five cents each, by addressing the "Commissioner of Patents, Washington, D. C."

Having thus fully described my invention what I claim as new and desire to secure by Letters Patent of the United States is:—

1. In a grinding mill, the combination with a circular frame having supporting means, of an oblong housing, means to support said housing upon the circular frame, said housing being adapted to receive crushing rollers, the end walls of the housing having elongated slots through which the bearings of one of the rollers extend, said end walls also having wings for the reception of adjusting screws, and an angular shaped flaring hopper engaged within the end walls of the housing adapted to convey food particles into said housing to be crushed by said rollers. 50

2. A grinding mill comprising a pair of crushing rollers having shafts extending beyond each end thereof, a single driving 60 pinion for each roller adapted for attachment to either end of the shafts, and a circular driving gear engaging both of said pinions for rotating said crushing rollers, one pinion being at the end of one shaft and 65 the other pinion at the opposite end of the other shaft when the gear is rotated in one direction and on the opposed ends of said shafts when the gear is rotated in the opposite direction whereby said rollers will be 70 caused to rotate toward each other at all times.

In testimony whereof I have signed my name to this specification in the presence of two subscribing witnesses.

MINOR HARRIS.
